AIR CONDITIONING APPARATUS

Leonard C. Smith, New York, N. Y., assignor to
 Heating Ventilating & Air Conditioning Co.,
 Inc., New York, N. Y., a corporation of New
 York

Application September 7, 1934, Serial No. 743,034

6 Claims. (Cl. 257—137)

This invention relates to apparatus for warming, cooling or otherwise conditioning air, and has for one of its objects the provision of a simple, compact and inexpensive apparatus particularly well adapted for conditioning the air of single rooms, although of course not limited to single rooms, the apparatus being of such a nature that it can be installed near the ceiling where it is out of the way and does not present an unsightly appearance.

In the drawing accompanying the application: Fig. 1 is a view showing the apparatus installed;

Fig. 2 is a section on the line 2—2 of Fig. 1;
 Fig. 3 is a section on the line 3—3 of Fig. 2;
 and

Fig. 4 is a sectional elevational view of a modification.

Referring to the drawing in detail, my conditioning apparatus includes a casing comprising a body portion 1 within which I mount plates referred to hereinafter as conditioning plates. These plates designated 2 and 3 are of corrugated metal extending from top to bottom of the body portion 1 of the casing of the apparatus. These plates which are wound or bent in the form of a spiral are spaced apart by lugs 4.

The space between the plates 2 and 3 is for the circulation of either a cooling medium such as cold water or a warming medium such as warm water, this conditioning medium being admitted to the inner end of the spiral through pipe 5. The water circulates through the spiral space between the plates 2 and 3 and discharges from the apparatus through pipe 6 which may lead back to the supply. It will be understood that my apparatus comprehends the use of fluids other than water. The air to be conditioned is drawn into the casing 1 by a fan 7 mounted at the top of the apparatus immediately above the center of the apparatus, this fan being driven by electric motor 8 mounted on the bottom of the casing.

In the convenient arrangement shown in Fig. 1 air is drawn from the room 9, upwardly through duct 10 in one wall thereof, through intake 11 in the apparatus. From thence it passes along the spiral passageway between the convolutions provided by the plates 2 and 3, counterflow to the conditioning medium, finally being discharged by the fan 7 through duct 12 back into the room 9 again.

As mentioned above the fan 7 is driven by a motor 8 secured to the bottom 13 of the casing 1 of the apparatus, the shaft of this motor ex-

tending upwardly through the space 14 in the center of the apparatus.

The lower end of the conditioning plates 2 and 3 may be closed by channel members 14 welded or otherwise secured to the bottom 13 of the casing of the apparatus while the upper end of these plates may be closed by similar channel members 15 welded or otherwise secured to a plate 16 across the top of the casing, this plate 16 and the cover 17 of the casing being sealed at 18 to the body portion 1 of the casing. The fan 7 is completely enclosed as shown.

The intake 11 of the device or apparatus as seen in Fig. 3 extends from top to bottom of the apparatus and at this intake opening I provide 15 a removable filter which may take the form of a wire mesh tube 20 filled with any suitable material 21, such as cotton for example.

The tube 20 may be removed from time to time and the filtering material 21 replaced or 20 cleaned.

The conditioning fluid, for example, water, and which may be taken from a suitable source of supply, circulates throughout the entire space provided by spirally winding the plates 2 and 25 3 and inasmuch as these plates additionally are of corrugated metal, it will be seen that the conditioning fluid is obliged to contact with a very large surface. By the same token the air to be conditioned and which travels counterflow to the 30 conditioning fluid must contact with this extensive surface, thereby providing a very compact apparatus capable of handling continuously a large volume of air.

To reduce the speed of the air passing through 35 the apparatus to insure its thorough cooling or heating, as the case may be, I provide baffles 22 in the space between the convolutions of the spirally bent plates 2 and 3.

In the modification shown in Fig. 4 I have provided a construction similar to that already described, in that I employ corrugated metal plates 2 and 3 wound or bent into a spiral. In this construction additionally I employ pipes 23 which are wound spirally, first in one direction and 45 then in the opposite and laid between the plates 2 and 3. This construction is advantageous where the conditioning fluid is under pressure, it being understood that in this embodiment of the invention the conditioning fluid is circulated 50 through the pipes 23 lying in the space between the plates 2 and 3 instead of merely through this space as in the first form described.

It is to be understood that changes may be made in the details of construction and arrange- 55

ment of parts above described within the spirit and scope of my invention.

What I claim is:—

- 5 1. Air conditioning apparatus comprising in combination an enclosing casing having an intake and a discharge, a plurality of plates within the casing wound in the form of a spiral with the convolutions of the spiral in spaced relation, an air intake for the casing adjacent the outer periphery of the spiral, an air discharge adjacent the inner end of the spiral, means for drawing air into said intake and circulating the same between the convolutions of the spiral in contact with the surfaces of the said plates and for discharging the air from the casing, and means for admitting a conditioning fluid to the space between the plates of the spiral for circulation through the spiral out of contact with the air to be conditioned and discharged from the spiral to the exterior of said casing.
- 10 2. Air conditioning apparatus comprising in combination an enclosing casing, a pair of plates within the casing, said plates being spirally wound with the convolutions of the spiral in spaced relation for the circulation of air in a spiral path through the space thus provided, baffle plates in said space arranged in spaced staggered relation to each other, and means for circulating a conditioning fluid through the space between the said plates, counterflow to and out of contact with the air flowing through the first mentioned space between the convolutions of the spiral.
- 15 3. Air conditioning apparatus comprising in combination an enclosing casing, a pair of corrugated metal plates within the casing, said plates being wound in a spiral with the convolutions of the spiral in spaced relation, air-circulating means for drawing air into the casing and forcing the same through the spiral passageway provided by the spacing of the convolutions of the spiral and discharging the air from the casing at the center of the spiral, and means for circulating a conditioning fluid through the spiral passageway provided by the spacing of the plates, counterflow to the passage of the air.
- 20 4. Air conditioning apparatus comprising in combination an enclosing casing having an intake and a discharge, a pair of corrugated metal plates wound in a spiral disposed within said

casing, the outer end of the spiral being disposed adjacent the casing intake, the inner end of the spiral being disposed adjacent the outlet of the casing, a fan mounted at the outlet of the casing for drawing air into said casing and forcing the same along the spiral space between the convolutions of the spiral and for finally discharging the air from the casing, and pipes connected to the inner and outer ends of the spiral for supplying conditioning fluid to the spiral space between the said plates for circulation through said space counterflow to the passage of the air circulating through the space between the convolutions of the spiral.

5 5. Air conditioning apparatus comprising in combination an enclosing casing, a pair of spaced corrugated metal plates within said casing and extending vertically thereof, said plates being wound spirally with a space between the convolutions of the spiral, said space terminating at an elongated vertically extending opening in the wall of said casing, a motor mounted on the lower end of said casing, an armature shaft therefor extending upwardly through said casing, a fan at the upper end of said shaft driven by said motor for drawing air through the side of the casing and circulating the same through said space between the convolutions of the spiral in contact with the outer corrugated surfaces of said plates and discharging it from the upper end of the casing, and means for circulating a conditioning fluid through the spiral space between said plates in contact with the inner corrugated surfaces of said plates counterflow to the air passing along the outer surfaces of said plates.

6. Air conditioning apparatus comprising in combination an enclosing casing, a pair of spaced corrugated metal plates within said casing wound spirally with a space between the convolutions of the spiral, spacer members between the metal plates, baffle plates in the spiral passageway between the convolutions of the spiral, means for drawing air into the casing for circulation in the space between the convolutions of the spiral, a removable filter in the path of the air entering the casing, and means for circulating a conditioning fluid between the plates counterflow to the air.

LEONARD C. SMITH.
